(57) **CLAIM**

The ornamental design for a pen, as shown and described.

DESCRIPTION

FIG. 1 is a perspective view of a pen, showing my new design;

FIG. 2 is a right side elevational view thereof;

FIG. 3 is a left side elevational view thereof;

FIG. 4 is a top plan view thereof;

FIG. 5 is a front elevational view thereof;

FIG. 6 is a rear elevational view thereof;

FIG. 7 is a bottom plan view thereof;

FIG. 8 is a perspective view of the pen cap in FIG. 1 shown separately for ease of illustration;

FIG. 9 is a right side elevational view thereof;

FIG. 10 is a left side elevational view thereof;

FIG. 11 is a top plan view thereof;

FIG. 12 is a front elevational view thereof;

FIG. 13 is a rear elevational view thereof;

FIG. 14 is a bottom plan view thereof;

FIG. 15 is a perspective view of the pen barrel in FIG. 1 shown separately for ease of illustration;

FIG. 16 is a right side elevational view thereof;

FIG. 17 is a left side elevational view thereof;

FIG. 18 is a top plan view thereof;

FIG. 19 is a front elevational view thereof;

FIG. 20 is a rear elevational view thereof; and,

FIG. 21 is a bottom plan view thereof.
